United States Patent Office.

JACOB VALENTINE, OF BOUND BROOK, FRANCIS HARRIS, JR., OF ELIZABETHTOWN, NEW JERSEY, AND CHAUNCY BARNES, OF NEW YORK, N. Y., ASSIGNEES TO DANIEL R. PRATT, OF NEW YORK CITY.

Letters Patent No. 100,693, dated March 8, 1870.

IMPROVEMENT IN RAILWAY-RAIL SPLICE.

The Schedule referred to in these Letters Patent and making part of the same.

To all whom it may concern:

Be it known that we, JACOB VALENTINE, of Bound Brook, Somerset county, FRANCIS HARRIS, Jun., of Elizabethtown, and State of New Jersey, and CHAUNCY BARNES, of the city and State of New York, have invented a new and improved Mode of Uniting and Securing the Ends or Junctions of the bars of Railroad Iron; and do hereby declare that the following is a full and exact description of the same, reference being had to the accompanying drawings and to the letters of reference marked thereon.

Figure 1 is a perspective drawing, showing the tongue of the rail on the outside.

Figure 2 is a perspective view of the jacket, with the groove attached thereto.

Figure 3 is a perspective view, showing the two ends united together, with the jacket fastened together thereto, by which means the same is firmly secured.

Figure 4 is a section, showing the end view of the rail and the jacket, with the tongue and groove.

To enable others skilled in the art to make and use my invention, I will proceed to describe its construction and operation.

Fig. 1, letter A represents the tongue or projection, about three-fourths of an inch wide, and one-half an inch thick, or thereabouts, rolled on the outside of the bars of railroad iron, (the rail being the same as the H-rail in common use,) about midway between the upper and lower surfaces, extending the whole length of the bars, with a wrought-iron jacket or flange.

Fig. 2, letter B represents the groove in the jacket, corresponding with and fitting over the tongue on the outside of the rail, covering or lapping over the joints or junctions of the rails about two feet long, and forming a complete tongue and groove, as seen at fig. 4, letters b b, extending about one foot, more or less, each way from the ends of the same.

Fig. 3, letter C represents the two ends butting together, and fastened together by means of the jacket D, which is bolted fast to the rails by means of four screw-bolts a a a a, passing through slot-holes c c c c in both the rails and jacket of sufficient length to al-

low for the contraction and expansion of the iron or rail.

We may also use a bar of iron on the inside of the rail, the bolts or screws passing through the jacket, rail, and iron bar, thereby uniting the junctions or ends of rails firmly together, with the view of obtaining an equal amount of strength at those parts a; at any other part, and of holding each part firmly to its place at the cross-joints, also to prevent the ends of the rails from battering or splintering, and producing a smooth even surface, the same as one continuous rail, thereby adding strength and durability to the road, and giving a steady, easy motion to the cars, being easily put down and readily adjusted or repaired, by simply taking out the four screw-bolts a a a a.

The jacket D, as shown in fig. 3, is of sufficient width to extend up to the top or even with the rail, forming a smooth surface of both the rail and flange or jacket.

By this combined arrangement, the common chair may be dispensed with, as the whole can be fastened down by means of the common spikes.

We do not claim as our invention the use of a mere jacket and screw-bolts for the union of the sections of rails or bars of railroads; but

What we do claim as our invention, and desire to secure by Letters Patent, is—

The tongue or projection, rolled on the outside of the bar of railroad iron, extending the whole length of the rails, with a groove rolled into the jacket to correspond with and fit over the tongue on the rail, forming a complete tongue and groove, the jacket being about two feet or more long, sufficient to produce the desired result, the top or upper edge of the jacket to extend even with the upper edge or surface of the bars of railroad iron, and bolted fast to the same by means of screw-bolts, as substantially described.

JACOB VALENTINE.
FRANCIS HARRIS, JUN.
CHAUNCY BARNES.

Witnesses:

WM. SINCLAIR,
T. G. CLAYTON.
